UNITED STATES PATENT OFFICE.

LEWIS A. ROBERTS, OF CARBONDALE, PENNSYLVANIA.

DESIGN FOR A SHOE-UPPER.

SPECIFICATION forming part of Design No. 30,382, dated March 21, 1899.

Application filed February 11, 1899. Serial No. 705,347. Term of patent 14 years.

To all whom it may concern:

Be it known that I, LEWIS A. ROBERTS, a citizen of the United States, residing at Carbon-dale, in the county of Lackawanna and State of Pennsylvania, have invented and produced a new and original Design for Shoe-Uppers, of which the following is a specification, reference being had to the accompanying drawing, forming a part thereof.

- o The drawing represents in perspective a shoe-upper embodying my present design.

The leading or material feature of the present design is the shoe-upper having the series of elongated and very narrow eyelets arranged parallel with the edges of the upper and in proximity thereto.

Referring to the said drawing, the letter A indicates a shoe-upper, the two edges of which

projecting close together at the front of the shoe form the lace-opening B, extending from the top of the upper down to the vamp C. Along each of the edges of the upper and in proximity to the lace-opening a series of very much elongated and narrow eyelets D are arranged, giving a peculiar slotted appearance to the edges of the upper, as illustrated in the drawing.

Having described my invention, what I claim as new is—

The design for a shoe-upper herein shown and described.

LEWIS A. ROBERTS.
